UNITED STATES PATENT OFFICE.

NATHAN WARSHAW, OF NEW YORK, N. Y.

FOLDABLE BOX.

Application filed June 11, 1924. Serial No. 719,349.

To all whom it may concern:

Be it known that I, NATHAN WARSHAW, a citizen of Russia, and a resident of New York, in the county of New York and State 5 of New York, have invented certain new and useful Improvements in a Foldable Box, of which the following is a full, clear, and exact specification.

This invention relates more particularly 10 to a class of knockdown containers.

My invention has for its object primarily to provide a box with a body and a separate cover designed to be employed for holding merchandise which may be displayed for 15 sale on show cases, counters and elsewhere without removal from the box, and the cover is of a form cut from a single foldable sheet or blank for providing when its parts are assembled a card for displaying 20 advertising matter in conjunction with the goods as well as providing for supporting the body of the box on an incline in the cover to conspicuously display the goods. The invention resides mainly in the provision 25 in conjunction with a suitable type of body of a separate cover folded from a single blank for providing a substantially rectangular body with a top plate, side walls and end walls whereby the cover may be 30 removably fitted over the box body in which merchandise may be packed. One of the end walls of the body of the cover is formed with an inwardly folded section, a flap section disposed upon the top plate and a display card 35 section in upstanding position adjacent the other end wall. By slitting parts of the blank at the juncture of the flap section with the display card section a bracket in the 40 form of an angular strip protruding above the flap section is provided for supporting on an incline the body of the box with its contents for being displayed, and the second end wall of the body of the cover has an inwardly folded section with a locking tongue 45 detachably engaging the edges of the slitted part of the flap section for releasably holding the flap section to the top plate.

A further object of the invention is to 50 provide a foldable box of a simple and efficient construction which may be made in any suitable size.

With these and other objects in view, the 55 invention will be hereinafter more fully explained with reference to the accompanying drawings forming a part of this specification in which similar characters of reference

indicate corresponding parts in all the views, and will then be pointed out in the claims at the end of the description.

In the drawings, Figure 1 is a plan of a 60 form of blank from which is foldable the cover of one form of the box embodying my invention.

Fig. 2 is a reduced perspective view of the blank showing it partly bent for being fold- 65 ed to form the cover.

Fig. 3 is a reduced perspective view showing the next stage of folding the blank to form the cover.

Fig. 4 is a reduced perspective view, partly 70 broken away, showing the cover when completely folded, and

Fig. 5 is an enlarged perspective view, partly broken away, showing the folded cover in position as used for supporting the 75 body of the box.

The box has a substantially rectangular body, as 10, which may be of any well known type cut and scored preferably from a single sheet or blank of card board or other flexible 80 material which is assembled by its parts being folded together for holding merchandise.

A separate cover 11 is provided for being removably fitted on the body 10 to inclose its contents, and this cover is cut from a single 85 sheet or blank, as 11^a Fig. 1, of card board or other foldable material to provide a substantially rectangular body 12 composed of a top plate 13, side walls 14, 14^a end walls 15, 15^a and pairs of infold strips 16, 16^a and 17, 17^a which are of sizes so that when folded together, as will be hereinafter more fully explained, the body 12 of the cover will be provided for being removably applied upon the body 10 of the box over its open top. 90

The end wall 15 of the body 12 of the cover has an inwardly foldable section, as 18, a flap section, as 19, and a display card section, as 20. At the juncture of the flap section 19 with the display card section 20 is a 100 bracket 21, and the end wall 15^a of the body 12 of the cover has an inwardly foldable section 22 with a marginal strip, as 23, having a locking tongue, as 24.

The blank 11 is scored lengthwise in 105 spaced relation to its side edges, as at A and B, for providing the side walls 14, 14^a of the cover 12, and the end walls 15, 15^a of the cover are formed by scoring, as at C and D, the blank in spaced proximity to its ends. 110 The top plate 13 of the cover is, therefore, of substantially a rectangular shape of a

2

size slightly larger than the body 10 of the box. One end part of the blank is slitted lengthwise, as at E and F, from the scoring C to its adjacent end to provide the pair of infoldable strips 16, 16^a, and the other end part of the blank is likewise slitted lengthwise, as at G, and H, to its adjacent end to provide the pair of infoldable strips 17, 17^a. In spaced relation to the end scoring 10 C the blank has two spaced parallel scorings, as I and J, to provide the inwardly foldable section 18 which is of a size approximately similar to the size of the end wall 15, and the central portion of the blank extending 15 from the scoring J is transversely scored, as at K, whereby the flap section 19 and display card section 20 are formed. The bracket 21 of the cover is provided by slitting, as at L and M, spaced parallel parts 20 lengthwise of the blank at the juncture of the flap section 19 with the display card section 20, and the blank is scored crosswise, as at N and O, between the ends of the slits L and M. The outer edges of the 25 parts of these slits at the scoring K may also be cut out, as at P and Q. In spaced relation to the end scoring D the blank has two spaced parallel scorings, as R and S, to provide the inwardly foldable section 22 30 and the marginal strip 23. The section 22 and the end wall 15^a are of approximately similar sizes, while the strip 23 is considerably narrower in width. In the central part of this strip are two spaced diverging slits, 35 as T and U, which extend from the scoring S to the second end of the blank to provide the locking tongue 24, and this tongue is of a width so that it may be disposed through the space of the flap section 19 between the 40 slits L and M whereby the wedge shaped ends of the tongue may be disposed in overlapping arrangement on the flap section when the bracket 21 is folded into position.

These parts are assembled to form the 45 cover 12 by the blank being folded on the scorings A, B, C, D so that the walls 14, 14^a and 15, 15^a are disposed in right-angular directions from the underside of the top plate 13. The blank may then be folded on the 50 scorings R and T for disposing the infold section 22 toward lapping position against the end wall 15 with the strip 23 lying upon the underside of the top plate 13, as shown in Figs. 2 and 3, and with the 55 folding of these parts the strips 17, 17^a are bent inwardly between the end wall 15^a and section 22 to releasably lock the side walls 14, 14^a to the end wall 15^a as shown in Figs. 4 and 5. The blank is then folded on the 60 scoring C for disposing the end wall 15 toward the adjacent ends of the side walls 14, 14^a and the strips 16, 16^a are infolded so as to lap upon the end wall 15, and the blank is folded on the scoring I for disposing the section 18 in lapping arrange- 65

ment on the strips 16, 16^a for releasably locking the end wall 15 and side walls 14, 14^a together. By folding the blank on the scoring J accordingly the flap section 19 will be disposed between the side walls and end 70 walls upon the underside of the top plate 13, and by folding the blank on the scoring K the display card section 20 may be disposed in upstanding position against the section 22 over the locking tongue 24. The 75 bracket strip 21 is then folded angularly for protruding inwardly of the folded body of the cover, as shown in Fig. 5, for supporting the body 10 of the box with its 80 contents on an incline, and by adjusting the locking tongue 24 so that its ends engage in lapping arrangement upon the parts of the edges of the slits L and M of the flap section 19 this flap will be detachably fastened for also holding the bracket 21 and the display card 20 in their unfolded positions, the display card serving to permit advertising matter to be displayed thereon, as occasion may require.

In the foregoing description, I have embodied the preferred form of my invention, but I do not wish to be understood as limiting myself thereto, as I am aware that modifications may be made therein without departing from the principle or sacrificing 90 any of the advantages of this invention, therefore, I reserve to myself the right to make such changes as fairly fall within the scope thereof.

Having thus described my invention, I 100 claim as new and desire to secure by Letters Patent:

1. In a box with a body, a separate cover cut and folded from a single blank, comprising a substantially rectangular body 105 with a top plate, side walls and end walls, one end wall having folded inwardly of the body a section with a protruding locking tongue adjacent the underside of the top plate and the other end wall having an 110 inwardly folded section with a flap section lying upon the underside of the top plate, and a bracket formed by parallel slits in the flap section, providing a strip folded angularly so that it protrudes inwardly of 115 the body of the cover, said locking tongue engaging parts of the edges of the slits opposite to the angular strip.

2. In a box with a body, a separate cover 120 cut and folded from a single blank, comprising a substantially rectangular body with a top plate, side walls and end walls, one end wall having folded inwardly of the body a section with a protruding locking tongue adjacent the underside of the top plate and the other end wall having an 125 inwardly folded section with a flap section lying upon the underside of the top plate and a display card section disposed in up- 130 standing position above said tongue and

against the first mentioned end wall section, and a bracket formed by parallel slits at the juncture of the flap section with the display card section providing a strip folded 5 angularly so that it protrudes inwardly of the body of the cover, said locking tongue engaging parts of the edges of the slits opposite to the angular strip.

3. In a box with a body, a separate cover 10 cut and folded from a single blank, comprising a substantially rectangular body with a top plate, side walls and end walls, one end wall having folded inwardly of the body a section with a protruding locking tongue 15 adjacent the underside of the top plate and the other end wall having an inwardly folded section, a flap section lying upon the underside of the top plate, and a display card section disposed in upstanding position 20 above said tongue and against the first mentioned end wall section.

4. In a box with a body, a separate cover 25 cut and folded from a single blank, comprising a substantially rectangular body with a top plate, side walls and end walls, one end wall having folded inwardly of the body a section with a protruding locking tongue adjacent the underside of the top 30 plate and the other end wall having an inwardly folded section, a flap section lying upon the underside of the top plate and a display card section disposed in upstanding position above said tongue and against the first mentioned end wall section, and a strip 35 cut-out of the flap and display card and folded angularly so that it protrudes inwardly of the body of the cover, said locking tongue engaging parts of the edges of the slits opposite to the angular strip.

40 5. In a box with a body, a separate cover cut and folded from a single blank, comprising a substantially rectangular body with a

top plate, side walls and end walls, one end wall having folded inwardly of the body a section with a protruding locking tongue, and the other end wall having a flap section lying upon the underside of the top plate and having a display card section disposed in upstanding position above said tongue, said locking tongue de- 45 tachably engaging the flap section.

6. A separate cover for a box, cut and folded from a single blank, comprising a substantially rectangular body with a top plate, side walls and end walls, one end wall 50 having folded inwardly of the body a locking tongue adjacent the underside of the top plate and the other end wall having an inwardly folded section with a flap section lying upon the underside of the top plate 55 and having a display card section disposed in upstanding position above said tongue and against the first mentioned end wall section, and means interiorly of the body for supporting the body of a box on an incline, 60 said locking tongue removably engaging the flap section.

7. A separate cover for a box, cut and folded from a single blank, comprising a substantially rectangular body with a top 70 plate, side walls and end walls, one end wall having folded inwardly of the body a locking tongue adjacent the underside of the top plate and the other end wall having an inwardly folded section, with a flap section 75 lying upon the underside of the top plate, and means interiorly of the body for supporting the body of a box on an incline, said locking tongue removably engaging the flap section.

This specification signed this 10th day of June, A. D. 1924.

NATHAN WARSHAW.
